UNITED STATES PATENT OFFICE

2,058,864

REFRIGERATING APPARATUS

Martin J. Goulooze, Grand Rapids, Mich., assignor to Kelvinator Corporation, Detroit, Mich., a corporation of Michigan

Application March 30, 1934, Serial No. 718,189

2 Claims. (Cl. 211—143)

This invention relates to refrigerator cabinets and more particularly to a shelf and tray construction therefor, it being the principal object to provide a refrigerator cabinet with a slidable service tray and a supporting shelf, so arranged that the tray will not obstruct circulation within the cabinet.

Another object is to provide a refrigerator cabinet with a tray supported on the bottom of the food compartment, but spaced therefrom and supporting a service tray in such manner that the tray will not interfere with circulation within the compartment.

With the above and other objects in view, the present invention consists of certain features of construction and combinations of parts to be hereinafter described with reference to the accompanying drawing, and then claimed.

In the drawing which illustrates a suitable embodiment of the invention:

20 Figure 1 is a perspective view of a refrigerator cabinet, showing the shelf and tray construction disposed therein;

25 Figure 2 is an enlarged fragmentary perspective view of the cabinet, showing the tray in partially withdrawn position;

Figure 3 is an enlarged fragmentary front elevation of the cabinet, showing the shelf and tray in front elevation;

30 Figure 4 is a section taken approximately on line 4—4 of Figure 3; and

Figure 5 is a fragmentary section taken approximately on line 5—5 of Figure 4.

Referring to the accompanying drawing in which like numerals refer to like parts throughout the several views, the shelf A is supported within the refrigerator cabinet B on the bottom wall 10 of the food compartment, and may be of any suitable construction. However, I have

40 shown the shelf, for the purposes of illustration, as comprising a frame formed from a single piece of bar material. The frame as here shown comprises a pair of spaced front and rear horizontal portions 12 and 13 respectively having down turned end portions 14, and in which each end portion 14 of the front portion 12 is integrally connected with the corresponding end portions of the rear portion 13 by a side portion 15.

45 The side portions 15 seat on the bottom wall 10 of food compartment as shown in Figures 1 and 2 and space the shelf surface above the bottom wall 10. The shelf surface is preferably comprised of a plurality of spaced bars 16 extending

50 between and suitably secured to the horizontal

front and rear portions 12 and 13 to permit free circulation within the food compartment.

The shelf is removably supported on the bottom wall 10 of the food compartment but in order to prevent inadvertent displacement of the same in the direction of the cabinet door opening, the depending portions 14 of the rear end portion 13 are connected by a horizontally extending strip 17 arranged to be disposed rearwardly of a pair of upwardly extending fingers 18 or projections 18 secured to the bottom wall 10 adjacent to the rear wall 19 of the cabinet as shown in Figures 4 and 5. Obviously, however, other means for holding the shelf A against inadvertent forward movement may be employed.

55 The service tray 20 which may be of dished form as shown in Figures 2 and 4 or of other suitable shape, is slidably supported as previously mentioned, on the shelf. In order to accomplish this, the shelf is provided with a pair of spaced horizontal guides 22 having bent end portions 21 securely welded to the depending end portions 14 as shown in Figures 2 and 5 so that the service tray 20 may be slidably supported thereon.

20 The service tray 20 is therefore supported on the shelf in spaced relation with respect to the bottom wall 10 of the food compartment and is arranged to be slidably removed from the shelf and also to be disposed beneath the shelf surface 30 composed of the bars 16 when it is not desired to use the same.

25 The shelf and tray are also so arranged adjacent the bottom of the food compartment that the tray when disposed beneath the shelf, will not interfere with circulation within the food compartment and also will not interfere with the circulation about and below articles that may be supported by the tray supporting shelf.

30 The shelf, while it is shown as comprising a single piece frame and horizontal bars 16 may be of any suitable construction having its supporting surface supported on the bottom of the food compartment in spaced relation to provide a space adjacent the bottom for the reception of 45 the service tray 20.

35 The tray 20 may be partially withdrawn and utilized as a rearranging tray for receiving articles while other articles are being placed on or removed from or rearranged on the other refrigerator shelves or it may be utilized primarily as a service tray capable of being bodily removed from its supporting shelf.

40 It is to be clearly understood that minor and obvious changes may be made in the embodiment 55

shown and described without departing from the spirit and scope of the present invention as defined in the appended claims.

What I claim is:

- 5 1. In a combined service tray shelf unit the combination of a horizontal shelf member adapted to be mounted in the food storage compartment of a refrigerator, a service tray slidably supported on said shelf member below the 10 horizontal surface thereof and arranged to permit free circulation within the compartment and about said shelf member, said shelf member comprising a one piece frame composed of spaced horizontal end portions, each having depending 15 portions, and horizontal portions extending between the depending portions at each side of the shelf and adapted to seat on the bottom of said compartment, a service tray guide member secured between the depending portions on each 20 side in parallel relation spaced above each of said horizontal portions, a plurality of article supporting members extending between and secured to said horizontal end portions, and a bar extending between the rearmost depending portions, and means in free engagement with said last mentioned bar for preventing movement of said shelf member during withdrawal of said service tray from said shelf.

2. In a combined service tray shelf unit, the combination of a horizontal shelf member adapted to be mounted in the food storage compartment of a refrigerator, said shelf member comprising a one-piece frame composed of spaced 5 horizontal end portions, each having depending portions, horizontal portions extending between the depending portions at each side of the shelf and adapted to fit on the bottom of said compartment, a service tray guide member secured 10 between the depending portions on each side in parallel relation spaced above each of said horizontal portions, said guide members having curved end portions for projecting the guide portions inwardly towards each other, a service tray 15 slidably supported between said guide members, a plurality of article supporting members comprising substantially parallel rods extending between and secured to said horizontal end portions, a bar extending between the rearmost depending portions and means in free engagement with said last mentioned bar for preventing movement of said shelf member during withdrawal of said service tray from said shelf.
